BRUSHMAKING MACHINE AND METHOD

John G. Baumgartner, Oswego, Ill.

Application February 2, 1949, Serial No. 74,106

22 Claims. (Cl. 300—21)

1

This invention relates to the manufacture of brushes, and particularly to the manufacture of small brushes adapted for use in applying lacquer and the like.

The present application is a continuation-in-part of my pending application, Serial No. 742,530, for Brush, filed on April 19, 1947, now Patent No. 2,558,334 issued June 26, 1951.

Brushes now commonly used in applying lacquer, such as for applying fingernail polish and for use in art work, include a small cylindrical handle into which are secured bristles normally made of pony or camel hair or other natural fiber. Such natural hairs and fibers, in their native condition, are not uniform in size and shape, and to provide a brush of high quality careful selection of the fibers is necessary. This requires a large amount of labor, making the brush relatively expensive. Failure to properly select the bristles results in a brush in which the bristles become tangled and matted, and the lacquer or other material being applied is unevenly spread, leaving ridges and lines.

Bristles made of synthetic fibers such as nylon have a high degree of uniformity and can be produced very inexpensively. Prior attempts to use synthetic bristles in brushes have been unsatisfactory, however, due largely to the fact that when the bristles are cut off to uniform lengths, the ends thereof tend to enlarge or become mushroomed. The enlarged ends of the bristles prevent the lacquer or other coating material from being applied smoothly, so that the result is substantially no better than that obtained when poorly selected or unselected natural fibers are used.

An object of the present invention is to provide an improved machine for the production of small inexpensive brushes having synthetic bristles, whereby the quality of these brushes compares favorably with that of brushes using the best grade of natural bristles.

Another object is to provide an improved method of making a small brush with synthetic bristles having the characteristics required for smoothly spreading lacquer or similar coating material.

A further object is to provide novel means adapted to form pointed or tapered ends on the bristles after they are trimmed, so that the lacquer flows smoothly from the bristles without clogging or matting them, and a still further object is to insure that all of the bristles in the tuft are thoroughly finished.

As a feature of the invention I have made pro-

2

visions for tapering the ends of the bristles to conical points by passing the bristles of an assembled brush in a particular manner across the face of a rotating grinding wheel.

Another feature is the use of oscillatory means for intermittently rotating the brushes in the course of their passage across the grinding wheel, so that all sides of the tuft are brought into contact with the wheel.

Still another feature is a unique arrangement whereby the ends of the individual bristles in each tuft are spread out on the face of the grinding wheel to insure their intimate contact therewith, such arrangement including means to flatten each bristle tuft momentarily while it is engaged with the grinding wheel.

The foregoing and other objects, features and advantages of the invention will be better understood from a study of the following description taken in conjunction with the accompanying drawings, wherein:

Fig. 1 is a front view of a machine for grinding the bristles of a brush, such machine embodying the principles of the invention;

Fig. 2 is a top view of the machine of Fig. 1;

Fig. 3 is a sectional view along the line 3—3 of Fig. 1;

Fig. 3a is a fragmentary elevational view along the line 3a—3a of Fig. 3.

Fig. 4 is an enlarged longitudinal sectional view of a complete brush assembly in which there is included a brush made in accordance with the principles of the invention;

Fig. 5 is an enlarged view showing the natural configuration of the ends of the bristles when cut;

Fig. 6 is an enlarged view showing the configuration of the bristles after being ground;

Fig. 7 is a fragmentary plan view of a second embodiment of the present invention;

Fig. 8 is a perspective view of the complete machine in which the second embodiment is included;

Fig. 9 is a partial front elevation showing the conveyor means of the second embodiment;

Fig. 10 is an enlarged view of a portion of the conveyor and parts associated therewith;

Fig. 11 is a plan view of the bristle finishing apparatus;

Fig. 12 is a vertical section on the line 12—12 of Fig. 11;

Fig. 13 is a vertical section on the line 13—13 of Fig. 11; and

Fig. 14 is a partial perspective view of the brush finishing apparatus.

In practicing the invention, the brushes are placed on a conveyor chain which moves step-by-step past a cylindrical grinding wheel in a direction parallel to the axis thereof. The brushes are disposed with their handles extending transversely of the chain and with the ends of their bristles contacting the grinding wheel. As the brushes are moved in step-by-step fashion across the face of the grinding wheel, they come to rest a number of times while they engage the rotating wheel. Oscillatory means are provided to produce rotation of the brushes as they progress across the grinding wheel. In one embodiment of the invention, the brushes are rotated between steps, and in another embodiment the brushes are rotated while they are at rest. The brush rotating mechanism includes a pair of gripping members that extend along the path of movement of the brushes. Cyclic motion is imparted to one or both of these members for intermittently causing them to grip and twirl the brush handles, whereby all sides of each tuft are brought into engagement with the grinding wheel. I have sought to insure also that each individual bristle in a tuft is conically tapered to a point. In a modified form of the invention disclosed herein the brushes are twirled while they are undergoing translational movement, and each time the brushes come to rest, their bristles are clamped in such a way that the ends of the bristles are spread out flat against the grinding wheel.

Referring briefly to the form of brush assembly illustrated in Fig. 4, which is typical of those produced, by the use of my invention, the brush proper includes a handle 10 which may be made of any suitable plastic material with a tuft of bristles 11 secured in one end thereof. A finger gripping portion 12 is secured to the other end of the handle 10, and customarily this finger gripping portion 12 serves as a cap for a small container of the type in which nail lacquer or other liquid to be applied by the brush is kept. The handle 10 has an enlarged head portion 14 adapted to be tightly secured in a tubular projection 15 on the finger gripping portion 12. The finger gripping portion may include threads 16 for engaging similar threads on the container, and a sealing washer 17 so that a tight seal can be made thereby. The bottom end of the handle 10 has a cavity 18 which extends axially within the handle to a depth at least equal to the diameter of the handle. The bristle tuft 11 is received within the cavity 18 and is secured directly to the handle 10 by a staple 19 straddling the bristles in the tuft for anchoring the tuft at the bottom 20 of the cavity. This manner of securing the bristles in the brush is covered in my prior Patent No. 2,438,515. The illustrated brush assembly is drawn on a large scale in Fig. 4. Actually, the handle 10 is about $\frac{1}{8}$ of an inch in diameter, and the tuft of bristles 11 is of the order of $\frac{3}{32}$ inch in diameter. The overall length of the handle 10 and tuft 11 is about two inches.

The bristle tuft 11 is composed of a plurality of bristles 21 which are doubled back about the loop formed by the staple 19, as illustrated in Fig. 4. The bristles are made of a synthetic fiber, such as nylon, and are of a uniform diameter, about .004 of an inch. The tuft fits tightly within the cavity 18 and is positioned in the cavity to such a depth that a relatively tight tuft of bristles is formed. While nylon fibers have been found to be satisfactory for a nail

polish brush, rayon or other synthetic fibers may be more suitable in other applications.

After the fibers are formed into a tuft and secured in the handle as illustrated in Fig. 4, the tuft must be finished in order to provide a brush which is suitable for applying lacquer or the like. The ends of the fibers are cut off squarely to form an even end of the tuft. It has been found that when the nylon fibers are cut off the ends thereof are enlarged or become mushroomed as is illustrated in Fig. 5. Fig. 5 was made from a microscopic photograph of fibers approximately four-thousandths of an inch in diameter, the enlarger ends being illustrated at 22.

Although the tuft of bristles after having the ends thereof trimmed forms a brush having an even edge, it is apparent that the enlarged ends of the bristles will not permit lacquer or similar material to be spread smoothly as is required in the application of fingernail polish or as is required in art work or other application. It has been found, however, that if the nylon bristles are ground to provide ends which are of generally pointed configuration with a long taper, a brush having such bristles works very satisfactorily, being generally superior to high class pony or camel hair brushes. Fig. 6 is a greatly enlarged representation of the bristles, being taken from an actual microscopic photograph of bristles as shown in Fig. 5 after having the ends thereof ground. The grinding operation may be performed by moving the end of the tuft of an assembled brush over the face of a rotary grinding wheel. Fig. 6 illustrates bristles which have been ground to provide a taper of approximately 15 to 1 on the ends thereof. That is, the length of the taper is approximately 15 times as great as the diameter of the bristles since the bristles taper to a point. Bristles having a taper of 8 to 1 have been found to be satisfactory for a lacquer brush, but a longer taper is preferable. In addition to providing generally pointed ends on the fibers to provide a brush which will spread lacquer evenly, the grinding of the ends tends to roughen the surface of the fibers providing recesses which help to hold the lacquer on the bristles.

In Figs. 1, 2 and 3 there is illustrated one embodiment of the invention which is suitable for grinding the bristles of a brush to provide a taper thereon as previously described. In Fig. 1 there is illustrated a continuous chain 25 supported by four sprocket wheels 26 so that the chain can move in the manner of a conveyor. The chain includes a plurality of pivotally connected links 27 each of which has a groove 28 therein adapted to receive the handle 10 of a brush. After the bristle tuft 11 is stapled to the handle 10 of the brush and the ends of the bristles are cut straight across the tuft to make the bristles uniform in length, the assembled brushes are placed in the grooves 28 in the chain 25. In the apparatus shown in Figs. 1, 2 and 3, the chain is adapted to move in a counter-clockwise direction so that the brushes will be inserted in the grooves 28 at the left-hand side of the top portion thereof as shown in Fig. 1. A stationary guard 29 is provided around the sides and bottom of the moving chain to hold the brushes in position in the grooves 28 in the chain. As illustrated in Fig. 2, as the brushes are moved along the bottom side of the guard by the chain 25, the bristle tufts are passed along the surface of a grinding wheel 30 and in a direction axially thereof. The grinding wheel is mounted on a

shaft 31 which is supported for rotation by frame members 32 and 33. The shaft 31 is driven at constant speed by any suitable means, pulleys 34 driven by V-belts 35 being illustrated by way of example.

For the purpose of turning the brushes as the bristle tufts pass along the grinding wheel, so as to taper the ends of the bristles, a mechanism for rotating the handles of the brushes is provided. This mechanism is supported by a frame plate 40 which includes bearings for four shafts 41, 42, 43 and 44. As is apparent from Fig. 1 the shaft 42 includes a sprocket wheel 45 thereon which is driven by a chain 46. Each of the shafts includes toothed gears 47 thereon which mesh with a large gear 48 also supported for rotation by frame plate 40. Through the medium of the large gear 48 and the gears 47 the movement of shaft 42 is transmitted to the shafts 41, 43 and 44, and as indicated by arrows in Figs. 1 and 3a, each of these shafts are adapted to rotate in a clockwise direction. The shafts 41, 42, 43 and 44 have pins 51, 52, 53 and 54, respectively, at the ends thereof, the pins being of smaller diameter than the shafts themselves and being positioned eccentrically with respect to the shafts. A pair of gripping members 55 and 56 are supported by the pins 51 to 54, inclusive, the gripping members including vertically extending slots 57 in which the pins are received. Washers 62 are secured to the ends of the pins 51 to 54, inclusive, to hold the gripping members 55 and 56 thereon. The gripping members 55 and 56 are further supported by springs 58 and 59 which are supported by portions 60 and 61 secured to the frame plate 40. The lower gripping member 56 has a serrated top edge 63 as is indicated in Fig. 1. The top gripping member 55 has a resilient insert 64 in the bottom edge thereof as is clearly shown in Fig. 3. The members 55 and 56 are adapted to grip the enlarged portions 14 of the brush handles 10 as illustrated in Fig. 3 and as will be more fully described.

The chain 46 for driving the turning mechanism is driven by a sprocket wheel 65 secured to shaft 66 which may be driven at a constant speed by any suitable means. For driving the conveyor chain 25 from the shaft 66, crank 67 is secured to the end of the shaft. Movement of the crank is transmitted to the conveyor chain by the use of a toothed driving wheel 68 which is connected to one of the sprocket wheels 26 and a ratchet mechanism for driving the wheel 68 in accordance with movement of crank 67. This ratchet mechanism includes arm 69 (Figs. 1 and 3) pivotally connected to the crank 67, arm 70 which is pivotally connected to arm 69 and which supports finger 71, and spring 72 which holds finger 71 against the teeth of the wheel 68.

Considering now the operation of the mechanism for turning the brushes, it is apparent that as the shafts 41 to 44 are simultaneously rotated the pins 51 to 54 eccentrically positioned thereon will describe a circle. The top gripping member 55 positioned on the pins 51 and 53 will be oscillated to the right and left. The springs 58 together with the weight of the gripping member 55 will cause the member to be normally held in a downward position. Similarly the gripping member 56 will be made to oscillate to the right and left due to the rotary movement of the pins 52 and 54, the springs 59 tending to hold the member 56 in its up-most position. However, the slots 57 in the gripping member 55 are not sufficiently long to absorb all of the vertical

movement of the eccentrically positioned pins so that when the pins 51 and 53 are in their highest position they will engage the top of the slots 57 in the member 55 to cause the gripping member 55 to be raised slightly so that the resilient insert 54 thereof will be lifted off of the brush handles. At the same instant the pins 52 and 54 will engage the bottoms of the slots 57 in the gripping member 56 to cause the member 56 to be withdrawn from the underside of the brush handles. In Fig. 1 the pins 51 to 54 are shown in the position in which the gripping members 55 and 56 are held away from the brush handles. Figs. 3 and 3a show the gripping members engaging the portions 14 of the brush handles.

The common driving mechanism for the turning mechanism and for the conveyor chain 25 comprising the sprocket wheel 65 and the crank 67 which are driven by the same shaft (66) permits the movement of the conveyor chain 25 to be timed so that each brush is moved from one position to the next position while the gripping members 55 and 56 are released therefrom. The action of the ratchet mechanism is such that the movement of the chain 25, will be a step-by-step process and each movement will be accomplished in a very short time so that the chain will be stationary a large portion of the time. This, therefore, permits the gripping members to be released from the brush handle for only a very short period of time so that during substantially the entire time that the brushes are passed over the grinding wheel 30 the handles are being turned.

The turning of the handles of the brushes, with the resulting change of position of the bristle tufts on the grinding wheel, will cause all sides of the tuft to be acted upon by the grinding wheel. The tuft, while being ground, contacts the grinding wheel 30 at an angle, as illustrated in Fig. 3. A projecting ridge 73 is provided on the plate 40 against which the ends of the handles 10 rest so that the bristle tufts will be properly positioned with respect to the wheel. The bristles are slightly spread as shown in Fig. 2, when they contact the grinding wheel. It is obvious that the character of the grinding wheel used, the speed of operation of the grinding wheel, and the position and movement of the bristle tuft with respect to the grinding wheel will all affect the taper obtained on the bristles.

The apparatus illustrated in Figs. 1, 2 and 3 produces conical tapers on the bristles which contact the grinding wheel. To insure that all of the bristles in each tuft are brought into contact with the grinding wheel, resort may be had to the embodiment of the invention illustrated in Figs. 7 to 14. In this embodiment, as in the first embodiment, the brushes are moved step-by-step axially across the face of a grinding wheel 30, but in the present instance they are rotated only while they are moving laterally. Each time the brushes come to rest while they are in grinding position, a spreader element 82 clamps down upon the tufts of the brushes and causes the tufts to be momentarily flattened horizontally so that the bristles are spread out sideways. The effect of this is illustrated in Fig. 7, where the bristles 21 of a tuft 11 are shown "fanned out" on the face of the grinding wheel 30, with each individual bristle being brought into contact with the wheel. The above-described steps of rotating the brushes and spreading the bristles are repeated alternately several times as each brush progresses across the wheel. This insures that each bristle in the tuft is thoroughly ground to a conical point

as shown in Fig. 6, and this is accomplished without any permanent deformation of the tufts.

Referring now to Fig. 8, which is a general view of the modified machine, a supply of brush handles 10 is kept in a handle magazine 84. The handles are placed by hand into a guideway 86 from which they are fed in succession to a conveyor chain 88 that carries the brushes in a horizontal path from one side of the machine to the other. Bristles are kept in a bristle magazine 90 from which they are fed downwardly by gravity. A tuft forming and stapling mechanism generally designated 92 intermittently withdraws tufts of bristles from the magazine 90 and staples these tufts into the handles of the brushes which have been carried by the chain 88 into the stapling position. A suitable tuft forming and stapling mechanism which may be used in the present machine is disclosed in detail in my pending application, Serial No. 480,354, filed on March 24, 1943. After being stapled into a brush handle, the ends of each tuft are trimmed automatically before the brush advances to the grinding wheel 80. The brushes are carried by the chain 88 across the face of the grinding wheel 80, and the finished brushes (that is, the handle and tuft combinations as 10—11 illustrated in Fig. 4) are fed to a brush magazine 94 from which they are removed by hand and packed into boxes.

Referring now to Figs. 8 and 9, brush handles 10 are taken from the handle magazine 84 by hand and are placed in the guideway 86 in side by side relation. A spring-urged, pivoted presser arm 96, Fig. 8, works in a curved portion of the guideway 86 for urging the handles 10 toward a delivery point at the end of the guideway 86 directly above the left end of the chain 88, Fig. 9. There the foremost handle 10 comes to rest on a yieldable support 98 which normally is urged by a spring 100 into a horizontal position. A stationary structure 101 affords a vertical guideway 102 extending from beneath the support 98 to the chain 88. A slide 104 is mounted for vertical reciprocatory movement in the structure 101. A rocker 106 operated by a cam 108, Fig. 9, periodically lowers and raises the slide 104. Each time the slide 104 descends, it pushes the foremost brush handle 10 from the guideway 86 down onto the chain 88. The support 98 yields to permit passage of the handle 10 through the guideway 102. As shown best in Fig. 10, each link of the chain is recessed, as indicated at 110, to receive and support a brush handle 10. The operation of the slide 104 is timed so that a handle 10 is deposited on each pair of links in the chain 88.

The chain 88 passes around sprocket wheels as 112, Fig. 9, and the horizontal upper pass of the chain 88 slides along a chain guideway provided on the upper edge portion of a block or frame 114 that extends from one side of the machine to the other. A series of three pusher pawls 116, Figs. 9 and 12, mounted on the upper ends of rocker arms 118 cooperates with the underside of the chain 88. A stationary, horizontally extending bar 120 disposed above the chain 88 serves to maintain the brush handles 10 seated in the recesses 110 in the chain links and prevents upward displacement of the chain 88. The rockers 118 are actuated in unison by a cam 122, being oscillated back and forth to impart intermittent step-by-step movement to the chain 88. Thus, the brush handles 10 are carried by the chain 88 to the stapling position where the bristle tufts are secured thereto, thence to the grinding position where the bristles are

finished, and finally the finished brushes are stripped from the chain 88 and are deposited in the brush magazine 94, Fig. 8. A weighted lever 124 prevents the brushes from spilling back out of the magazine 94 onto the chain 88.

The brush handles 10 project a substantial distance beyond the front edges of the chain 88 and guide block 114. A pivoted sensing finger 126, Fig. 9, rests at its lower end upon these projecting portions of the handles 10 that are being carried by the chain 88. The lower end of the finger 126 is of sufficient length horizontally so that the finger 126 is maintained in an elevated position so long as there are brush handles 10 on the chain 88. If the supply of brush handles in the guideway 86 should become exhausted, so that no more brush handles 10 are carried by the chain 88, the finger 126 drops by gravity and causes a switch 128 controlled thereby to close. This completes a circuit to a suitable warning device such as a lamp or buzzer, advising the operator that the guideway 86 is empty.

A supply of synthetic bristles may be placed on the tray 130, Fig. 8, at the front of the machine. The operator passes the bristles through a stationary comb 132 and then places them in the bristle magazine 90. From the magazine 90 the bristles are fed by gravity to the tuft-forming and stapling mechanism 92, which secures the bristles to the brush handles 10 carried by the chain 88. Then the brushes are carried by the chain 88 in step-by-step fashion across the face of a cylindrical grinding wheel 80 as indicated in Fig. 11. A guide strip 134, Figs. 11, 12, 13 and 14, cooperates with the head portions 14 of the brush handles 10 to hold the brushes with their bristle tufts 11 engaging the face of the grinding wheel 80. The axial length of the grinding wheel 80 is sufficient to accommodate a large number of brushes. The brushes are carried step-by-step axially across the grinding wheel 80 by the chain 88, and each brush comes to rest a number of times while cooperating with the wheel 80.

A bracket 136, Figs. 11 and 14, supports a set of gears 138, 139 and 140 which are constantly driven. The gears 138 and 140 are mounted on shafts 142 and 143 which extend through bearings 144 and 145 supported by the bracket 136 rearwardly of this bracket. The shafts 142 and 143 terminate in cranks 146 from which crank pins 148 extend through vertical slots 150 in an oscillatory gripping member 152, as best shown in Figs. 12 and 13. The gripping member 152, consists of a bar 154 (in which the slots 150 are located) and a resilient insert 156 in the lower edge portion of the bar 154. The gripping member 152 is positioned above the enlarged head portions 14 of the brush handles 10. Beneath the head portions 14 there is disposed a stationary gripping member or bar 158 having a serrated upper edge, as shown in Figs. 11 and 14. This serrated upper edge is positioned to engage the handle heads 14 from beneath.

The gripping member 152 is supported by the crank pins 148. A weight 160 on the bar 154 tends to urge the upper gripping member 152 into engagement with the brush handles 10. The slots 150 in the bar 154 are of such character that when the crank pins 148 are in their upper positions, the gripping member 152 is lifted clear of the brush handles 10. As the crank pins 148 descend, the gripping member 152 is shifted to one side and the crank pins 148 enter the lower portions of the slots 150 where there is a certain

amount of vertical lost motion. The gripping member 152, after being brought to bear up on the heads 14 of the brush handles 10, is moved tangentially across the brush handles. This causes the brush handles to be rotated on the chain 88 for turning the bristle tufts 11 of the brushes which are engaged with the grinding wheel 80.

Normally the oscillatory mechanism for rotating the brush handles is covered by a guard 162, Fig. 8, which is shown swung open in this view. The timing of the parts is such that the brush handles are rotated only while the chain 88 is in motion, the purpose of this arrangement being explained presently. Notches 164 in the upper edge of the stationary hold-down bar 120, Figs. 11, 13, and 14, afford clearance for the crank pins 148. A guard 166, Fig. 8, encloses the gear mechanism for operating the rotative parts.

When the brushes come to rest intermediate their successive steps of movement, the bristle spreading means becomes effective. As shown in Figs. 11, 13 and 14, the bristle tufts project over a ledge 168 formed on an extension of the block or frame 114. This ledge 168 is located close to the face of the grinding wheel 80 approximately $\frac{2}{3}$ of the distance back from the ends of the bristle tufts 11. Directly above the ledge 168 is located the spreader element 82, which comprises a flat bar positioned vertically and extending parallel to the axis of the grinding wheel 80. The spreader bar 82 is carried by rocker arms 170 that are mounted on a small shaft 172 journaled in bearings on the upper end of the bracket 136. A rocker 174, Fig. 11, extending from the shaft 172 is actuated by suitable linkage means 175 (Fig. 8) for intermittently rocking the shaft 172. This causes the arms 170 carrying the spreader bar 82 to be rocked up and down.

While the brushes are at rest, the spreader bar 82 moves down to clamp and flatten the portions of the bristle tufts 11 disposed on the ledge 168. This causes the bristles 21 in each tuft 11 to be spread out laterally so that the individual bristles lie flat against the face of the grinding wheel 80. In other words, the bristles 21 are caused to "fan out" as shown in Fig. 7.

As the brushes pass across the face of the grinding wheel 80, being alternately subjected to rotating and bristle-spreading operations, the ends of the bristles are ground to uniform conical points. Uniform tapering of the bristles is assured by these spreading and rotating operations, whereby the individual bristles are made to engage the grinding wheel for equal periods of time. Thus, it will be seen that the machine produces a brush having synthetic bristles which is far superior to brushes of this type produced by prior machines and methods. The brushes are much cheaper in price and are equal in quality to brushes made with the best selection of natural fibers.

The illustrated embodiments of the invention exemplify the manner in which the principles of the invention may be applied. Other embodiments coming within the scope of the present teachings are possible, and it is intended that such modifications shall be included within the spirit of the appended claims.

I claim:

1. In the manufacture of a brush having a tuft of synthetic bristles extending from a handle, the method of tapering the ends of the bristles which comprises the steps of holding the brush

by its handle with the end portions of the bristles engaging a rotating grinding wheel, and momentarily flattening the portion of the tuft intermediate the handle and the ends of the bristles for spreading the bristle ends flat against the face of the grinding wheel.

2. In a machine for producing brushes each having a tuft of bristles extending from a handle, apparatus for finishing the ends of the bristles comprising in combination a grinding wheel, a conveyor spaced from said grinding wheel adapted for carrying brushes into cooperation with said wheel, said conveyor having provisions for supporting each brush with the bristle tuft extending into contact with the face of said wheel and the brush handle extending away from said wheel, means supporting and driving said conveyor in said apparatus, a pair of relatively movable brush handle gripping members mounted adjacent said conveyor, cyclically operable actuating means operatively connected with one of said gripping members for producing relative oscillatory movement of said gripping member toward and away from the other and angularly with respect to the conveyor which would be tangentially relative to any brush handles on the conveyor thereby to rotate each brush handle intermittently while the bristles are being ground, relatively movable spreader members and means for supporting the same for a relative movement of one member with respect to the other in a space between said grinding wheel and said conveyor and adapted for engagement with opposite sides of the bristle tuft of a brush, and reciprocatory actuating means operatively connected with said one spreader member for producing relative movement of said spreader member toward and from the other.

3. In a machine for securing bristle tufts to brush handles, the combination of a handle delivery guideway, a horizontally extending conveyor chain having longitudinally spaced recesses therein for individually receiving brush handles, intermittently operable actuating means operatively connected to said conveyor chain for imparting step-by-step movement thereby, means adapted to bear on brush handles in said guideway for feeding brush handles in succession to a predetermined delivery position above said chain, a yieldable support means for holding each brush disposed in such delivery position, and a vertically reciprocable slide operable in timed relation with the movement of said chain for moving the brush handles successively from said yieldable support through said guideway to be deposited on said chain.

4. The method of tapering the end portion of synthetic bristles for a brush to provide a pointed tapered configuration on each bristle, such method comprising the steps of holding the bristles adjacent the end portions thereof to maintain such end portions spread on the rotating surface of a grinding wheel, grinding the bristle end portions to grind one side of each end portion, releasing the bristles, rotating the bristles to present another side of the end portion of each bristle to the rotating surface of the grinding wheel, and alternatively repeating the steps of holding, grinding, releasing, and rotating the bristles while intermittently moving the same in a line of travel relative to the grinding wheel.

5. The method of tapering the end portions of bristles for a brush to provide a pointed tapered configuration on each bristle, such method com-

11

prising the steps of clamping the tuft of bristles adjacent the end portions of the bristles in the tuft to spread out the bristles fanwise and to maintain such end portions spread on the rotating surface of a grinding wheel, grinding the bristle end portions thereby, releasing the bristles from the clamping, rotating the tuft of bristles to present another side of the end portion of each bristle to the rotating surface of the grinding wheel, and simultaneously moving the bristles along a path of travel relative to the grinding wheel, and alternatively repeating the steps of holding, grinding, releasing, and rotating the bristles while intermittently moving the same.

6. In the manufacture of a brush having a tuft of bristles and a handle with the bristles extending longitudinally from the end of the handle, the method of grinding the outer end portions of the bristles into conical tapers which comprises conveying a plurality of such brushes relative to a moving abrasive surface, applying the end portions of the bristles thereof in a fanwise pattern to grind such end portions on the moving abrasive surface, rotating each conveyed brush at the handle to rotate it completely around during an entire grinding operation and simultaneously rotating the bristle tuft therewith to present the end portions of the bristles to the abrasive surface in different circumferential positions so that during the complete grinding operation each bristle tuft is turned completely and the bristles ground in a conical taper at the end portions on the moving abrasive surface.

7. The method of tapering by grinding the end portions of the bristles in the handle of a brush, which comprises supporting a plurality of brushes at the handles on a moving conveyor, applying the end portions of the bristles to a moving abrasive surface while conveying the brushes relative to the moving abrasive surface, spreading the end portions of the bristles fanwise on the moving abrasive surface and grinding such end portions while so spread fanwise, and rotating the brushes during a grinding operation so as to bring all sides of the end portions of the bristles into engagement with the abrasive surface and thereby grind a conical taper on such end portions.

8. In the manufacture of a brush with a handle having a tuft of bristles extending longitudinally from the end of the handle, the method of grinding the outer end portions of the bristles into conical tapers which comprises conveying a plurality of such brushes relative to a moving abrasive surface with the end portions of the bristles thereof in engagement with the moving abrasive surface, clamping the bristles of each conveyed brush between the ends thereof, spreading the end portions of the bristles fanwise against the moving abrasive surface, rotating each brush being conveyed, and continuing to intermittently clamp the bristles and continuing to rotate the brushes so that during the complete grinding operation the bristles are engaged on all sides at the end portions by the moving abrasive surface.

9. A machine for producing a brush having a handle with a tuft of conically pointed bristles extending therefrom, said machine including in combination abrasive-surfaced means movably supported in the machine, driven conveyor means for supporting brushes thereon mounted to move adjacent said abrasive-surfaced means and relative thereto, brush handle engaging-means including a bar mounted adjacent the path of movement of said conveyor means, means operating

12

said engaging means and said conveyor means in timed relation and means mounting said bar and moving said bar in an oscillatory path and intermittently into and out of engagement with the 5 conveyed brush handles to rotate the same, a bristle tuft spreader member in the machine spaced laterally from the conveyor in the direction of the abrasive surfaced means, and means connected to said member to raise and lower the same in timed relation to the engaging means.

10. A machine for continuously grinding the bristle ends of the bristle tufts of a plurality of unitary brush handle and bristle tuft workpieces and comprising a movable abrasive surface 15 adapted to simultaneously receive in grinding engagement the bristle ends of a plurality of said workpieces, means to move said abrasive surface, conveyor means movable relative to said abrasive surface and adapted to simultaneously convey a plurality of said workpieces parallel thereto, means to intermittently move said conveyor means, guide means positioned parallel to said conveyor means and adapted to continuously constrain said workpieces towards said surface in 20 a manner to flex the bristle ends of said workpieces into grinding engagement with said abrasive surface during the passage of said workpieces parallel to said abrasive surface, gripping means adapted to intermittently grip and rotate said workpieces to rotate the bristle ends during their 25 engagement with said abrasive surface and timed to be operated when said conveyor means is moving, and means operative to engage and spread said bristle ends into fanwise engagement with said surface and timed to be operated when said conveyor means is not moving, said gripping means including a pair of gripping bars having a length sufficient to simultaneously grip a plurality of said workpieces and positioned substantially parallel to said conveyor means and abrasive surface, a first one of said bars being fixed below the plane of said conveyor, the second one of said bars being movably positioned above the 30 plane of said conveyor and movable towards the first bar to thereby grip the plurality of workpieces between the opposing surfaces of said bars, and means to oscillate said second bar to and from said first bar with a component motion parallel to said fixed bar during the interval when 35 said workpieces are gripped between said bars to thereby rotate said workpieces.

11. The invention of claim 10 in which said first gripping bar includes a serrated gripping surface and said second gripping bar includes a resilient gripping surface.

12. A machine for continuously grinding the bristle ends of the bristle tufts of a plurality of unitary brush handle and bristle tuft workpieces and comprising a movable abrasive surface having a width transverse to its direction of movement sufficient to simultaneously receive in grinding engagement the bristle ends of a plurality of said workpieces, means to move said abrasive surface, conveyor means movable in one direction parallel to the width of said abrasive surface and adapted to simultaneously convey a plurality of said workpieces parallel to the width thereof, means to intermittently move said conveyor, guide means positioned parallel to said conveyor means and adapted to continuously constrain said workpieces towards said surface in a manner to flex the bristle ends of said workpieces into grinding engagement with said abrasive surface during the passage of said workpieces parallel to the width of said abrasive surface.

sive surface, gripping means operative to intermittently grip and rotate said workpieces to rotate the bristle ends during their engagement with said abrasive surface, said gripping means including a pair of relatively movable gripping bars having a length substantially equal to the width of said abrasive surface and positioned substantially parallel to said conveyor means and abrasive surface, one of said bars being positioned below the plane of said conveyor, the other of said bars being positioned above the plane of said conveyor, and means to intermittently oscillate each of said bars to and from each other with component motions parallel to said conveyor and in opposite directions during the interval when a plurality of said workpieces are gripped between said bars to thereby rotate said workpieces.

13. A machine with a movable abrasive surface and mechanism for handling a plurality of workpieces each of which comprises a handle with a bristle tuft thereon adapted to be ground at its outer end portion by the movable abrasive surface so as to provide a conical taper on the outer end portions of bristles in the tuft, said machine mechanism including in combination workpiece conveying means moving adjacent the movable abrasive surface and adapted to carry a plurality of workpieces thereon with the bristle tufts thereof extended toward the movable abrasive surface, bristle tuft spreader means including a pair of members, means causing relative movement in said members to clamp therebetween a bristle tuft intermediate the ends of the tuft to spread out the same in a fan shape and maintain the outer end portions of bristles in the tuft against the movable abrasive surface and alternately to release the bristle tuft from said clamping, means adapted to act on the handles of the conveyed workpieces to rotate the workpieces relative to the conveyor means and the movable abrasive surface, and means for timing the movement of the conveyor means and said bristle tuft spreader means so that the conveyor means is stopped while the spreader members maintain the outer end portions of bristles in the tuft against the movable abrasive surface.

14. A machine with a movable abrasive surface and mechanism for handling a plurality of workpieces each of which comprises a handle with a bristle tuft thereon adapted to be ground at its outer end portion by the movable abrasive surface so as to provide a conical taper on the outer end portions of bristles in the tuft, said machine mechanism including in combination a workpiece conveyor adjacent the movable abrasive surface to carry a plurality of workpieces thereon with the bristle tufts extending toward the movable abrasive surface, means supporting and driving said workpiece conveyor in said machine, tuft spreader means including relatively movable spreader members and means for moving at least one of said members relative to the other to clamp therebetween a bristle tuft of a workpiece and spread out the same in a fanwise configuration with end portions of bristles in the tuft on the movable abrasive surface to be ground thereby, means adapted to act on the handles of the workpieces on the conveyor to rotate said handles and thereby rotate the workpieces relative to the conveyor and movable abrasive surface, and cyclical timing means in the machine acting relative to the conveyor driving means and to the tuft spreader means to stop the conveyor means while the spreader members of said spreader

means clamp between the same and maintain a bristle tuft spread fanwise for grinding the end portions of bristles therein on the movable abrasive surface.

5 15. In the manufacture of a small brush of the order of 2 inches in overall length having a tuft of synthetic bristles each of which bristles is no more than .004 inch in diameter extending from a handle of the order of $\frac{1}{8}$ inch in diameter, the method of tapering the outer ends of synthetic bristles in the tuft which includes the steps of supporting the small brush at the handle, clamping and flattening a portion intermediate the ends of the bristle tuft from opposite sides to spread the tuft into a fanwise shape at its end portion, grinding bristles in the tuft at the outer ends thereof while spread out fanwise, releasing the tuft from the clamping, rotating the small brush to a position at which to compress, spread, and grind another side of the bristle tuft at the end portion thereof and hence the outer ends of bristles therein, and repeating said steps for taper grinding the outer ends of synthetic bristles in the tuft.

20 16. In the manufacture of a small brush having very thin and flexible synthetic bristles extending in a tuft from a handle, the method of tapering the outer ends of synthetic bristles in the tuft which includes the repetitive operation of performing the steps of moving the small brush along a path, clamping and momentarily flattening the bristle tuft to spread it at its end portion into a fan, grinding the end portion of synthetic bristles in such tuft, releasing the bristle tuft from the clamping, and rotating the small brush sufficiently to make another side of the bristle tuft available for the grinding of end portions of synthetic bristles therein.

25 17. In a machine for producing brushes which have a single compact tuft of bristles extending from a handle with the bristles being thin and individually yieldable over the length thereof, apparatus for finishing the outer end portions of the bristles by grinding the same, said apparatus including in combination, moving grinding means, brush handling means for retaining a brush in a predetermined position with the bristles thereof extending toward the grinding means, a bristle rest so constructed and so positioned relative to said brush handling means that a bristle tuft of a retained brush will engage said bristle rest on one side of said tuft intermediate the brush handle and the outer ends of the bristles, fanning means for acting on the other side of the bristle tuft on said bristle rest and cooperating with said bristle rest to spread out the outer end portions of bristles and momentarily apply outer bristle-end-portions to the moving grinding means in a fanwise pattern so that a substantial number of the bristle-end-portions in the tuft are presented to the grinding means for grinding, said brush handling means operating to turn a brush retained thereby to present other bristles to the grinding means, and means in the apparatus cooperating with said brush handling means and said fanning means for interruptedly and repeatedly operating said two latter means to momentarily present in the fanwise pattern different parts of the bristle tuft to said moving grinding means for grinding outer bristle-end-portions into a tapered configuration.

30 18. In a machine for producing brushes which have a single compact tuft of bristles extending from a handle with the bristles being thin and individually yieldable over the length thereof, and

15

the machine having grinding means for finishing the outer end portions of the bristles by grinding the same, the combination including supporting means for retaining a brush in a predetermined position with the bristles thereof extending toward the grinding means, a bristle rest so constructed and so positioned relative to said supporting means that the single bristle tuft of a brush on said supporting means will engage said rest on one side of said tuft at a position between the brush handle and the outer ends of the bristles, fanning means acting on the other side of the bristle tuft and cooperating with said bristle rest to spread out the outer end portions of bristles and apply outer bristle-end-portions to the moving grinding means in a fanwise pattern, means for rotating the brush at its handle where it is retained on the supporting means, and the combination also including means cooperating with said rotating means and said fanning means to operate said two means alternately and interruptedly and repeatedly to correspondingly present in such a fanwise pattern different parts of the single bristle tuft to said moving grinding means to grind outer bristle-end-portions into a tapered configuration by a plurality of grinding operations on the brush tuft.

19. In a machine for producing brushes which have a bristle tuft wherein the bristles extend from a handle and are each yieldable over its length and the machine having apparatus for finishing outer end portions of the bristles by grinding the same, said apparatus including in combination, movable grinding means, means for supporting a brush with the bristles extending toward the grinding means, and controllable means adapted to repeatedly and interruptedly spread out and apply the outer end portions of the bristles of a brush against the movable grinding means in a fanwise pattern, with said movable grinding means adapted to grind outer bristle-end-portions so spread thereon into tapered configurations, said controllable means including means acting on opposite sides of a bristle tuft at a position between the brush handle and the outer bristle ends to compress the bristle tuft at such position in a manner to spread the same in the fanwise pattern at the outer end portions of the bristles against the grinding means so that end portions of more bristles can be ground on the movable grinding means than would be ground without so spreading the bristle tuft.

20. In a machine for producing a plurality of brushes each having a tuft of bristles yieldable over their length and extending from a handle, and the machine having movable grinding means for finishing the outer end portions of the bristles, the combination including means for supporting a plurality of brushes simultaneously with the bristles of each extending toward the grinding means, and controllable means adapted to repeatedly and interruptedly spread out and apply the outer end portions of the bristles against the movable grinding means in a fanwise pattern for only a brief interval at each time of applying with the movable grinding means adapted to grind outer bristle-end-portions into tapered configurations, said controllable means including a machine portion against which tufts of the plurality of brushes engage and with such machine portion positioned relative to the movable grinding means such that the engagement will occur at a point between the brush handles and the outer bristle ends thereof, and means for simultaneously acting on the sides of all of the

16

plurality of bristle tufts opposite to the sides at the machine portion to simultaneously compress and spread in the fanwise pattern the outer ends of the bristle tufts so that outer end portions of more bristles can be ground on the movable grinding means than would be ground without so spreading the bristle tufts.

21. In the manufacture of a brush having a tuft of bristles extending from a handle therefor which bristles are each readily yieldable over the length thereof, the method of tapering outer end portions of bristles in the tuft which comprises the steps of presenting a brush to moving grinding means with the bristles in the tuft 10 extending toward the grinding means, momentarily acting on the bristle tuft so that it is flattened out from pressure applied on at least one side thereof at a position between the handle and the outer ends of the bristles to cause the 15 bristle-end-portions to spread fanwise, grinding outer bristle-end-portions spread fanwise on the grinding means, turning the brush handle to present other outer bristle-end-portions in the tuft to the grinding means, again momentarily 20 so acting on the bristle tuft for again spreading the outer bristle-end-portions fanwise, grinding other outer bristle-end-portions, and repeating the steps of flattening, of grinding, and of turning, for the purpose of grinding to a tapered configuration outer end portions of bristles in the 25 tuft. 30

35 22. In the manufacture of a brush, the method of tapering the outer end portions of yieldable synthetic bristles for a brush including the steps of presenting a tuft of bristles toward a moving grinding means, clamping the tuft momentarily at a point between the opposite ends of the bristles in the tuft to compress the tuft and spread out the end portions of the bristles at the outer end of the tuft and applying the spread bristle-end-portions fanwise on the grinding means, grinding outer bristle-end-portions spread fanwise on the grinding means, turning the tuft to present other bristle-end-portions at 40 45 such outer end of the tuft to the moving grinding means, repeatedly so clamping the tuft, so grinding bristle-end-portions, and so turning the tuft for the purpose of grinding to a tapered configuration end portions of bristles in the outer 50 end of the tuft.
